UNITED STATES PATENT OFFICE.

MANTON E. FOSS, OF WILDER, MINNESOTA.

PUMP.

1,392,928.

Specification of Letters Patent. Patented Oct. 11, 1921.

Application filed June 8, 1920. Serial No. 387,475.

To all whom it may concern:

Be it known that I, MANTON E. Foss, a citizen of the United States, and a resident of Wilder, in the county of Jackson and State of Minnesota, have invented certain new and useful Improvements in Pumps, of which the following is a specification.

My invention is an improvement in pumps, and the invention has for its object to provide a double cylinder pump, each cylinder of which is double acting, thus providing what is, in effect, a quadruple acting pump, fluid being drawn into the pump and ejected from each end of the barrel at each stroke of the plunger in each direction.

In the drawings:

Figure 1 is a vertical section through the improved pump;

Fig. 2 is a section on the line 2—2 of Fig. 1;

Fig. 3 is an enlarged detail section of the upper valve.

In the present embodiment of the invention the improved pump is composed of two similar cylinders 1 and 1^a, which, at their lower ends, are threaded into openings in the top of a casing 2, which is supported by a suitable base 3, the base having upstanding arms 4 which have inwardly extending lugs 5 at their tops, abutting the under face of the casing 2 and secured thereto, as shown.

Each cylinder 1 and 1^a has a lateral port 6 at its lower end which communicates with the chamber or casing 2, and a discharge pipe 7 leads upwardly from the chamber between the cylinders 1 and 1^a, the lower end of the discharge pipe being threaded into an opening in the top of the casing. At their upper ends the cylinders 1 and 1^a have lateral ports 8, which communicate by pipes 9, which may be of rubber or the like, with laterally extending nipples on a valve casting which is threaded on to the upper end of the discharge pipe 7, and which will be presently described in detail.

A plunger is arranged in each cylinder, each plunger consisting of an upper head 11 and a lower head 12, the said heads being frusto-conical and arranged with their small ends adjacent, and each head has threaded engagement with a stem 13. Referring to Fig. 1, it will be seen that the lower end of each stem 13 is reduced, as shown at 14, and that the reduced portion of each stem is threaded, as is also that portion of the body of the stem just above the reduced portion.

These portions are oppositely threaded, one, the body, being threaded with a left hand thread and the other, the reduced portion, with a right hand thread.

A sleeve 15 of leather or the like is arranged between the heads, the said sleeve fitting over the small ends of the heads, and it will be obvious that by turning the head 12 the sleeve 15 may be expanded, to compensate for wear, to secure better action of the pump. The stems 13 pass through stuffing boxes at the upper ends of the cylinder, to be later described, and they are connected with a two-part handle above the same. This handle, as shown, consists of a central sleeve 17 of metal, within which the stems 13 have threaded engagement, and a pair of handle members 18 of wood or the like, which are inserted into the sleeve from the opposite ends, and which have means for interengaging to lock them in place in the sleeve. One of these sections has a threaded axial stem as shown, and the other an axial recess for engagement by the stem.

At the lower end of each cylinder there is provided in the chamber 2 an internally threaded opening, with which is engaged a valve casing, consisting of an inner section 19 and an outer section 20. The inner section is a valve seat and guide and is threaded into the opening, and the outer section is threaded on to the reduced outer end of the inner section.

The outer section 20 of each valve casing has a marginal rib at its outer end and between this rib and a sleeve 21, which is held on the inner section, there is arranged a coil spring 22, the said spring acting to force the sleeve inwardly. The seat and guide 19 has a lateral port, as shown, and the sleeve 21 has a similar port registering therewith. A packing is arranged between the section 20 and the section 19. The valve 23 has a stem 24 which passes through the guide or inner section into the outer section and is encircled by a spring 25, which abuts at one end the section 19 and at the other a stop on the stem, the stop being in the form of a washer and cotter pin. The spring normally holds the valve closed.

The valve casing at the top of the cylinders consists of a section 10 which is threaded on to the upper end of the discharge pipe 7, a section 26 which has threaded engagement with the section 10, a section 27 which is a valve seat and guide and is

threaded into the section 26, and a section 28 which is threaded on to the section 27, the outer end of this section being reduced to receive the section 28. The upper end of 5 the discharge pipe 7 is reamed to form a valve seat with which coöperates a valve 29. The valve has a stem 30, which is hollow, and in which is slidable the stem 31 of a second valve 32 which coöperates with 10 the lower end of the section 26 of the casing, the said end being formed into a valve seat.

A coil spring 33 is arranged between the valves and acts normally to seat both valves. 15 Another valve 34 coöperates with the lower end of the section 7, this section being like the section 19 of Fig. 1. This valve has a stem 35 which passes through the guide into the section 28 and is encircled by a spring 20 36 arranged between the end of the section 27 and a stop on the stem 35. A sleeve 37, similar to the sleeve 21 of Fig. 1, encircles the section 27, and a coil spring 38 is arranged between the outer end of the section 25 28 and the sleeve, acting normally to push the sleeve toward the section 26, and, as will be seen, packings are arranged between the section 28 and the sleeve and between the sleeve and the section 26, and the 30 sleeve has a port which communicates with the lateral port of the section 27. The section 26 has oppositely extending nipples with which are connected the pipes 9 before mentioned, and a flexible hose 39 is 35 connected with the section 10 of the valve casing at a port 40 in the said section.

Referring to Fig. 1, it will be seen that the head 12 has longitudinally extending openings, whose axes diverge outwardly and 40 downwardly. Each of these openings 41 consists of two portions of unequal diameter, and a headed peg is arranged in each opening, the body of the peg passing through the portion of less diameter, while 45 the head moves in the portion of greater diameter. A spring 42 is arranged above each head and a plug 43 is threaded into the top of each of the openings. The bottom of the casing 2 is recessed to receive 50 these pegs when the plungers move downward to their limit. The arrangement is such that the pegs are extended through the bottom of the heads normally, but may yield upwardly. The sleeves 21 and 37, which 55 may be of brass or the like, are dust covers, and when the pump is not in use they are turned to bring their ports out of register with the ports of the valve seat and guide with which they coöperate.

60 Referring to Figs. 2 and 3, it will be seen that each sleeve has a radial rib at its outer end which is roughened, to permit them to easily turn. Referring to Fig. 1 it will be seen that each of the stuffing boxes before 65 mentioned consists of a cup shaped outer

section 16 which is threaded into the cylinder and a section 16^a which is threaded into the outer section. These sections have registering bores through which the upper ends of the stems 13 pass, and it will be noted 70 that the stems are reduced at their upper ends.

The packing 43 is arranged between the sections 16 and 16^a and the inner end of the bore in the cup shaped section 16 is 75 frusto-conical or reduced at its inner end. The inner end of the section 16^a is also tapered and it will be evident that when the section 16^a is screwed into the section 16 the packing will be expanded laterally to form 80 a tight closure. The arrangement tends to force the packing toward the stem.

At the junction of the reduced portion of each stem with the body thereof, the stem tapers, this tapering portion coming at the 85 packing when the plungers are near the bottoms of the cylinders. Thus when the stems move upwardly the packing will be expanded, forming a tight closure between 90 the packing and the stem. When the stems are pushed down as far as possible and the packing is tightened on them it will be obvious that when the stems are pulled up the packing is packed still tighter.

In order to expand the plunger it is only 95 necessary to push down the plunger until the pegs 42 will engage the openings in the bottom of the casing 2. When this is done by turning the stem in the proper direction, it will be evident that the lower head 100 12 will be turned up toward the upper head 11, since the said head 12 is held by the pegs, thus expanding the plunger. When the stem is so turned, both heads will remain fixed and both will be moved simultaneously toward each other.

In operation, when the plungers are moved upwardly from the position of Fig. 1, air 110 will be drawn into the lower ends of the cylinders past the valves 23, and air above the pistons or plungers will be ejected through the ports 8 into the casing 10, from whence the air will pass by the valve 32 to the hose 39. When the plunger moves downwardly the air below the plungers will be 115 forced out through the pipe 7, past the valve 29 and into the hose 39.

Air will be drawn into the upper ends of the cylinders past the valve 34. The valves 32 and 29 constitute a double check, the 120 valve 29 permitting the passage from the pipe 7 to the hose, but preventing passage of air from the casing 10 to the pipe 7. The valve 32, on the other hand, permits the passage of air from the cylinders to the section 125 10, but prevents passage of air from the pipe 7 to the cylinders.

I claim:

1. A pump comprising a pair of cylinders and a discharge tube arranged between 130

them and having a hose at its upper end, a plunger in each cylinder, means for simultaneously moving the plungers, a check valve at the bottom of each cylinder for admitting air thereto, lateral ports at the ends of the cylinders communicating with the discharge tube, checks at the top of the said tube for permitting the admission of air to the cylinders on the down stroke of the plungers and for preventing the passage of air from the discharge tube to the cylinders and for permitting the passage of air from the cylinders to the hose on the up stroke of the plungers and for preventing discharge of the air to the atmosphere.

2. A pump comprising a pair of cylinders, a discharge tube common to both cylinders and connected thereto at the opposite ends thereof, a plunger in each cylinder, means for simultaneously moving the plungers, a check valve at the bottom of each cylinder for admitting air thereto, checks at the top of the said tube for permitting the admission of air from the atmosphere on the downward stroke of the plungers and for preventing the passage of air from the discharge tube to the cylinders and for permitting the passage of air from the cylinders to the discharge tube on the up-stroke of the plungers and for preventing discharge of the air to the atmosphere.

3. In a pump, a cylinder and a plunger, said plunger comprising a stem, and a pair

of frusto-conical heads having threaded engagement therewith, said heads being arranged with their small ends adjacent and being oppositely threaded on to the plunger, and a sleeve of flexible material encircling the stem and engaging the small ends of the heads, the inner head of the plunger having a spring supported pins mounted to move inwardly and normally spring pressed beyond the inner end of the head, the cylinder having openings for engagement by the pins to prevent rotation of the head to permit the stem to be turned with respect thereto.

4. In a pump, a cylinder and a plunger, said plunger comprising a stem, and a pair of frusto-conical heads having threaded engagement therewith, said heads being arranged with their small ends adjacent and being oppositely threaded on to the plunger, and a sleeve of flexible material encircling the stem and engaging the small ends of the heads.

5. In a pump, a pair of cylinders, a pair of plungers therein, a sleeve, a link connecting each plunger with the sleeve and having a detachable connection with the sleeve, and a sectional handle, each section having a portion extending within the sleeve, the portions of the two sections having interengaging means releasable by turning the sections with respect to each other.

MR. MANTON E. FOSS.
